FIRING TABLE

Charles R. Davison and Elmer F. Seibel, Erie, Pa.,
assignors, by mesne assignments, to The Standard
Stoker Company, Inc., New York, N. Y., a
corporation of Delaware

Application May 2, 1936, Serial No. 77,481

4 Claims. (Cl. 110—101)

This invention relates to stoker devices and particularly to locomotive stokers of the type wherein fuel is mechanically conveyed from the locomotive tender to a point in the firebox below the grate and is then elevated through a suitable conduit to a point above the fire where it is acted upon by jets of steam or other fluid which project and distribute the fuel evenly over the fire.

The main object of my invention is to provide a novel and useful form of a sectional firing table for stokers of the type described, over which the coal or other fuel passes as it leaves the stoker and is distributed over the fire.

In stokers of the type described, a portion of the firing table projects into the firebox such a distance as to subject it to a high degree of heat and this portion burns away much faster than other parts of the firing table that do not extend as great a distance into the firebox. It is therefore an object of this invention to provide a firing table in which that portion which is more subject to deterioration may readily be detached, removed and replaced by a new section thus obviating the necessity of replacing the entire firing table when a portion thereof has deteriorated to such an extent as to preclude its further use.

More specifically, an object of the invention is the provision of a novel sectional firing table that is provided with new and improved means for attaching the sections together and that is cheap to manufacture, is simple in construction and which when assembled in place forms a compact, simple, efficient and economical unit. Other objects and advantages of our invention will become apparent from the following description when read in connection with the accompanying drawing wherein,

Fig. 1 is a central longitudinal vertical section of a portion of a locomotive with a stoker applied thereto and a firing table assembled therewith;

Fig. 2 is a plan view of the firing table with parts broken away showing its application to the stoker conduit;

Fig. 3 is a view in section on the line 3—3 of Fig. 2; and

Fig. 4 is a view in perspective of the adjacent end portions of two sections of the firing table shown detached.

Throughout the following description and 50 claims, the terms "forward" and "rearward" as applied to the portions of the firing table are used relative to the direction of delivery of fuel through the stoker.

On the drawing, the locomotive is designated 55 generally by the numeral 10 and is provided with

a boiler firebox 11 having a backwall or rear water leg 12 and the grates 13. The backwall 12 has a firing opening 14 therethrough above the cab deck 15. Fuel is conveyed from the locomotive tender (not shown) to the locomotive 10 through 5 a conduit 16 which houses a portion of the screw conveyor system 17. A conduit 18 is universally connected to the forward end of the conduit 16 and terminates in an upwardly curving elbow 19 which merges into the straight tubular conduit 10 or riser conduit 20. The straight tubular conduit 20 terminates in a D-shaped mouth 21 or fuel delivery opening above the level of the fire in the firebox 11.

Partially surrounding the straight tubular conduit 20 is a protecting grate 22 shielding the conduit 20 from the direct heat of the fire in the firebox 11. Surmounting and lightly fitting the conduit 20 and resting at its inner edge on lugs 23 projecting laterally from the external wall of 20 the conduit 20, is a metal plate or firing table 24. The top 25 of the table 24 is smooth and preferably flat, as illustrated, and is in substantially the same plane with the upper marginal edge of the mouth portion 21, permitting fuel to pass 25 freely thereover.

The table 24 is composed of a plurality of sections, a substantially U-shaped section 26 constituting the forward portion of the table and preferably a pair of sections 27 and 28 constituting the rearward portion of the table. The sections 27 and 28 are preferably, though not necessarily, formed symmetrically and obviously could also be joined to form an integral unit.

The ends of the U-shaped section 26 are each 35 recessed in the upper portion thereof as indicated at 29 and 30, leaving projections 31 and 32, respectively. The projections 31 and 32 are provided with the openings 33 and 34, respectively, extending vertically therein. The ends of the 40 sections 27 and 28 adjacent the recessed ends of the U-shaped section 26 are each recessed in the lower portion thereof as indicated at 35 and 36 leaving projections 37 and 38, respectively. The 45 projections 37 and 38 are provided on their under sides with the depending lugs 39 and 40, respectively.

The recesses and projections, and the openings and lugs are so related that when assembled, the projections 37 and 38 are received in the recesses 50 29 and 30, respectively, and the projections 31 and 32 are received in the recesses 35 and 36, respectively, to provide the top of the table with a level continuous surface broken only by the mating edges of the sections 26, 27 and 28, and 55

the lugs 39 and 40 are received in the openings 33 and 34 to prevent relative fore and aft and lateral movement between the sections.

The sections 26, 27 and 28 when assembled 5 are seated on the conduit 20 by engagement of the lugs 23 with that portion of the under side of the table 24 adjacent the inner marginal edge thereof. The sections 27 and 28 are provided with the openings 41 and 42, respectively, arranged 10 to receive bolts 43 and 44, respectively, for securely attaching the sections 27 and 28 to the conduit 20. Thus, when the firing table is assembled and bolted to the conduit 20, the sections 26, 27 and 28 forming the table are securely 15 locked together and movement relative to each other and relative to the conduit 20 is prevented.

The table 24 is supported a slight distance above the top of the grate 22, providing a space as shown at 45 to permit relative movement between 20 the parts due to uneven expansion and contraction between the parts caused by the extreme variations in temperature.

The sections 27 and 28 of the firing table may be cored as at 46 in order to reduce the weight 25 of the table and to reduce the cost of construction. The section 26, since it extends farther into the firebox and consequently subject to more rapid deterioration, is preferably of solid metal.

A recess 47 is formed in the wall of the conduit 20 adjacent its mouth 21 and is arranged to receive a pressure fluid jet distributor 48 arranged to receive steam or other fluid under pressure through the pipes 50 and having a plurality of jet openings 51 through which the fluid under pressure is discharged across the mouth of the conduit 20 and over the firing table 24.

The firing table, in stokers of the type described, since it is wholly within the firebox is necessarily subjected to an intense heat and in 40 time deteriorates to such an extent as to require replacement. In the present arrangement there is provided a three piece firing table, which is readily and conveniently assembled, all parts being rigidly secured in place in a practical and 45 simple manner, and in which one part may be replaced as deterioration occurs without the expense of replacing the entire firing table.

We claim:

1. A U-shaped firing table for stokers, said 50 table being formed in a plurality of sections, the curved portion of said U-shaped table forming one section and the straight portions of the U-shaped table forming the other sections, the opposite ends of said curved section each having a horizontal recess in the upper side thereof leaving a projection and each of said straight sections having formed at its end adjacent a respective end of said curved section a horizontal 55 recess in the lower side thereof leaving a projection, said recesses and projections being interfitted, the projections at the adjacent ends of said curved section and said straight sec-

tions being arranged in overlapping relation, one projection at each of the adjacent ends of a straight section and the curved section having a vertically extending lug formed therewith and the other projection at each of the adjacent ends of a straight section and the curved section having a vertically extending opening therein receiving said lug for securing the sections of said table together. 5

2. In combination with a firebox, a conduit 10 for delivering fuel to said firebox comprising an upwardly extending portion terminating in a fuel delivery opening, ledge-like means extending outwardly from said upwardly extending conduit portion subjacent the delivery end thereof, a firing table having a flat top face, said table being seated on said ledge-like means and fitting closely against the delivery end of said upwardly extending conduit portion, said firing table comprising a substantially U-shaped forward portion and a 20 rearward portion in contacting end to end relation, said forward portion being provided with a horizontal recess in the upper side of an end thereof leaving a projection and said rearward portion being provided with a horizontal recess 25 in the lower side of the end thereof adjacent an end of said U-shaped portion leaving a projection, the recess in said U-shaped portion receiving the projection left by the recess in said rearward portion and the recess in said rearward portion receiving the projection left by the recess in said U-shaped portion, said second named projection having a depending lug formed therewith and said first named projection having a vertically extending opening therein receiving said depending 30 lug for preventing relative longitudinal and lateral movement between said portions, and means for rigidly securing said rearward portion to said upwardly extending conduit portion for securing said U-shaped portion against movement with respect to said conduit portion. 35

3. As an article of manufacture, a forward section of a firing table for stokers, said section having a flat top surface and being substantially U-shaped in section parallel to said top surface, 40 said section being provided with a horizontal recess in the upper side of each of its end portions leaving a projection at each end portion, each of said projections having a vertically extending opening therein. 45

4. As an article of manufacture, a section of a sectional firing table for stokers, said section having a flat top face and being substantially spandrel shaped in section parallel to said top face, said section being provided with a horizontal recess in the lower side of one end thereof leaving a projection at said end, and a lug formed with and depending from said projection, said lug being indented from the marginal edges defining said projection. 50
